UNITED STATES PATENT OFFICE

WILLIAM J. BRUECKMAN, OF DETROIT, MICHIGAN

GOLF-TEE PACKET

Application filed June 22, 1928. Serial No. 287,378.

This invention relates to golf tee packets, and particularly to packets suitable for mounting a plurality of golf tees for convenient access thereto.

5 An object of the invention is to provide a packet or mounting for golf tees which is of sufficiently inexpensive construction to permit of its free distribution for advertising purposes.

10 Another object is to proportion a golf tee packet to fit the watch pocket of a garment, with a portion thereof projecting slightly from said pocket, and to adapt the heads of the tees to seat upon such projecting portion 15 so as to allow a ready removal of the tees from the packet without taking the latter from the packet.

A further object is to give a golf tee holder a substantial wedge shape, such as will facilitate its insertion in a watch pocket, and will at the same time provide two opposite faces of suitable area to carry advertisements.

A still further object is to provide a golf tee packet formed of a flexible sheet of material folded to the form of a casing within which are adapted to be inserted the shanks of a plurality of golf tees having their heads seating exteriorly upon said casing so as to provide for a ready removal of any of said 30 tees from the packet.

Still another object is to form a golf tee packet of a single sheet of material adapted to be folded to form a tubular casing and to utilize a plurality of golf tees mounted upon 35 said casing to maintain the tubular form thereof.

These and various other objects the invention attains by the construction hereinafter described and illustrated in the accompanying drawings, wherein:

Figure 1 is a perspective view of the herein disclosed packet showing a number of tees carried thereby.

Figure 2 is a longitudinal vertical sectional 45 view of the same.

Figure 3 is an elevational view of the same showing said packet inserted in a trousers' watch pocket.

Figure 4 is a view of the blank from which 50 the packet is formed.

In these views, the reference character 1 designates a blank substantially rectangular in shape and formed of cardboard or other suitable flexible sheet material. Said blank is divided by a plurality of parallel scoring 55 lines 2 into panels 3, 4, 5, 6 and 7, the panels 4, 5 and 7 being of substantially equal area and the panels 3 and 6 being likewise substantially equal and considerably more narrow than the panels 4, 5 and 7. The panels 3 and 7 60 are formed at opposite ends of the blank and the panel 6 is formed between the panels 5 and 7, the panels 4 and 5 being adjoined. The panels 3 and 6 are each similarly formed with a row of spaced circular scorings 8 which are 65 of a diameter somewhat less than the maximum diameter of the tapered shank of an ordinary wooden golfing tee.

In forming said blank into the desired packet, the same is folded upon the scoring 70 lines 2 to give it the tubular form illustrated in Figure 1, in which form the panels 4 and 5 have a spaced, opposed, acutely divergent relation and the panels 3 and 6 are overlapped, the panel 7 lying within said tubular 75 casing adjacent to the panel 4. When thus folded the scorings 8 of the panels 3 and 6 are in registration, and it is readily possible to insert through each registered pair of said scorings the tapered shank 10 of a golf tee 80 having the usual cupped head 9 seating exteriorly upon the panel 3. In thus mounting the golf tees in the cardboard packet, the shanks of the said tees are caused to slightly 85 enlarge the openings determined by the scorings 8 so as to fit quite snugly in said openings when the heads of said tees are pushed down to seat upon the panel 3. Thus the tees are frictionally retained in their proper assembly with the packet while readily removable therefrom.

Any desired advertisements (not shown) may be applied upon the panels 4 and 5 so as to be exposed at opposite sides of the packet when said blank is folded. It is a feature of the construction that a single operation suffices to print any desired subject matter upon the faces 4 and 5 and at the same time to produce the folding score lines 2 and the circular scores 8. This feature, together with the 100

simple manner of forming the packet from the blank and of mounting the tees in the packet, renders the production of the article quite inexpensive, this being in general an essential characteristic of an advertising novelty intended for free distribution.

In the same connection, it is highly important to note that the tees when inserted in the packet form a means for securely maintaining the proper tubular form of the packet, since the shanks of said tees pin together the overlapping panels 3 and 6.

By forming the packet with a flat top face to seat the heads of the tees and by converging the sides as they extend downwardly from said face it is made possible to easily insert the packet in the watch pocket of a garment at the same time so exposing the heads of the tees as to permit their ready removal without disturbing the location of the packet in said pocket.

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

20 What I claim is:

1. A golf tee packet comprising a sheet of flexible material folded to tubular form and having spaced side walls and inner and outer overlapping portions connecting said walls and formed with registering openings for receiving golf tee shanks, the inner of said portions having an extension therefrom interiorly adjacent to one of said side walls for resisting the thrust applied to said inner overlapping portion by insertion of golf tees in said packet.

2. A golf tee packet comprising a sheet of flexible material, folded to form a pair of acutely diverged and substantially intersecting side walls and inner and outer overlapping portions respectively joined with said side walls, said overlapping portions having registered openings proportioned to snugly receive the shanks of golf tees, the inner overlapping portion having an extension therefrom, extending adjacent to one of said side walls and abutting their intersection.

In testimony whereof I sign this specification.

65 WILLIAM J. BRUECKMAN.
